MARSHALL W. HANKS, OF MADISON, WISCONSIN

LIQUID-CONDUCTOR HEATER

Application filed March 16, 1929. Serial No. 347,547.

My invention relates to liquid-conductor heaters in which heat is generated by passage of electric current through a body of liquid in which spaced electrodes are sub-
5 merged.

The object of my invention is to provide a liquid-conductor heater of the above-designated character which shall ensure the flow of sufficient electric current through the
10 liquid to generate the desired degree of heat without metal-to-metal contact between electrodes and terminals and which shall embody a readily removable electrode to facilitate cleaning the heater parts which may
15 become coated with such solid materials as may be precipitated thereon during normal use.

Heretofore, it has been the usual, and supposedly necessary, practice to employ con-
20 ducting terminal members having metallic contact with the submerged electrodes in order to ensure proper current flow from the one to the other through the liquid.

Patent No. 1,683,071 granted to HanksCraft
25 Company September 4, 1928, on an applica-
tion filed by Max Mason and myself, dis-
closes, in Figs. 3 and 4 of its drawings, a
structure in which the electrical contact for
one of the electrodes comprises a terminal
30 stud 53 to which is screwed the electrode 42.
With this construction, it is necessary that
the electrode 42 make metallic electrical con-
tact with terminal stud 53. Should metallic
electrical contact fail, through dirt or corro-
35 sion of the electrode or terminal at point of
contact, the device would fail to function as
intended even though the contacts were wet.
There would be a small leakage of current
through the liquid between the terminal stud
40 and the electrode, but this would be entirely
inadequate to permit sufficient current to
pass through the circuit to operate the de-
vice. Again, Figs. 12, 13 and 14 show struc-
tures where the removable electrodes rest
45 on terminal studs 97 and 118. For the func-
tion of these structures, metallic contact be-
tween the terminal studs and electrodes is
imperative. If either the terminal stud or
the electrode becomes dirty or oxidized at
50 point of contact so that metallic electric con-

nnection fails, the device will not function as intended.

In Patent No. 1,683,069, also granted to HanksCraft Company September 4, 1928, upon an application filed jointly by Max
55 Mason and myself, actual metallic contact
must be made between the removable elec-
trode member and the terminal stud to
ensure sufficient current flow to produce the
desired results.

In this case, actual metallic contact must
be made between the removable electrode and
the terminal stud to ensure sufficient cur-
rent flow to produce the desired results. If
the terminal stud is dirty at the point of
60 contact, or the removable electrode itself
is dirty, by reason of the collection of lime
or sediment, actual metallic contact of the
electrode with the terminal stud will fail.
Under this condition, it will be necessary to
clean both the stud and the removable elec-
trode in order to reestablish adequate con-
tact for ensuring a sufficient flow of current
to make the electrodes function as intended.
However, if the contacts are dirty, so that
65 metallic connection is not established, and if
water or other conducting liquid is poured
in, there will be a small amount of current
flow, but not of sufficient volume to make
the device function as intended.

It will thus be seen that electrodes of
liquid-conductor heaters have heretofore
been connected to an electric circuit by
metallic means, in order that such heaters
might properly perform their functions.

My present invention relates specifically
to means for electrically connecting the cir-
cuit to one or both electrodes by using what
I shall call liquid contact. Fundamentally,
it involves the principle of so increasing the
90 area of the electrode and that part of a fixed
contact terminal located adjacent to it that
the leakage through the exposed wet surface
of such enlarged parts will be sufficient to
ensure adequate flow of current, even though
95 the electrode and the fixed terminal are not
in actual metallic contact.

Referring to the drawing,
Figure 1 is a vertical sectional view of a
100

liquid-conductor heater which illustrates the principle of my invention;

Figure 2 is a plan view of the heater shown in Fig. 1, the removable member of the structure being omitted;

Fig. 3 is a vertical sectional view of one embodiment of my invention;

Fig. 4 is a plan view of the device shown in Fig. 3, the removable electrode member being omitted;

Fig. 5 is a view, similar to Fig. 3, of another embodiment of my invention, and

Fig. 6 is a plan view of the device shown in Fig. 5, the removable electrode member being omitted.

Referring specifically to Fig. 1, the electrode container 14 may be of any suitable insulating material, such as porcelain, bakelite, etc., or a metal receptacle having a lining of insulating material. 1 and 2 are electrodes of suitable conducting material connected to the electric circuit through posts or studs 12 and 12^a. 3 is a removable plate which may or may not be perforated and is held, by gravity, in a position above electrodes 1 and 2, upon a ledge 13 of the container 14.

When a liquid conductor, such as water, is poured into the insulating container 14, an electrical connection is established between electrodes 1 and 2 through the liquid and the intermediate removable plate 3. In this case, the circuit is from one conductor of circuit 15 to electrode 1 through the liquid to plate 3 and from plate 3, through the liquid to electrode 2, and to the other side of the circuit 15.

When liquid is poured into the container and current is turned on, the water will become heated by reason of the current passing through it. Heating is approximately the same at both electrodes 1 and 2, so long as the water is not boiling. The moment the water starts to boil, the active bubbling will shift either to electrode 1 or to electrode 2 but bubbling seldom occurs over both at the same time. This phenomena of the water preferring not to boil on both sides at the same time, but to remain static on the one or the other side, discloses the possibility of using the water itself for adequate electrical contact for one or both electrodes, since evaporation is effected only by the formation of bubbles and, therefore, the portion of the liquid in which no bubbles are produced is merely a part of the electric circuit, i. e., in effect, a part of each of the adjacent metal electrodes.

While the form shown in Fig. 1 is operative, the electrodes require more area and more water than would be the case were the design refined, as shown in Figs. 3 to 5.

In Fig. 3, the contact terminal 4 is of sufficient area to ensure adequate electric-current flow to the electrode 6, when the surface

is wet, even though metallic contact is not established. The water, making liquid contact between the contact terminal 4 and electrode 6, will not boil to such extent as to interfere with the practical flow of current, for the reason that the area is excessive and the energy-loss low because of the thin film of water and excessive surface. This is equivalent to raising electrode 1 in Fig. 1 to a point where it almost touches the plate 3.

Another point of decided advantage in the arrangement shown in Fig. 3, is the fact that the contact terminal 4 is a complete ring. With an arrangement of this character, and the ring connected to the grounded side of the electric circuit, it is obvious that there would be little opportunity of receiving a shock from the moist surface of the container 14. This is a decided advantage in liquid-conductor heaters where they are used in homes or in any service where the hand might come in contact with the wet surface during the operation of the device.

In Fig. 5, the terminal contact buttons 7, 8 and 9 may be considered as sections of ring 4 shown in Fig. 3, as they are electrically connected together to form multiple contact—either liquid or metallic—between circuit 15 and electrode 11. The electrode 10 is formed to have symmetrical and insulated relations to terminal contact 7, 8 and 9 and is electrically connected to the circuit 15 through metallic studs or by means of suitably designed liquid terminal contact already described.

In each of the embodiments of my invention which have been shown and described, the spaced-apart electrodes are located in the bottom portion of a receptacle or container which is of non-conducting material or is lined with non-conducting material. The electrodes have a relatively large area, as a portion of their surface is given over to make adequate electrical connection with the terminal contact through the liquid film. The result of this arrangement permits sufficient current to flow to heat or vaporize the liquid between the electrodes, even though they are not in metallic contact with their terminals.

I have shown the electrode as a perforated metal plate but an unperforated plate may be utilized and, whether perforated or unperforated and whatever its form in other respects, it may be made of any conducting material.

It is also to be understood that heaters embodying my invention may be employed for various purposes, such as evaporating a measured quantity of water or other vaporizable liquid, or for merely heating a body of liquid—whether vaporizable or not—to a desired temperature for ultimate use per se or for imparting its heat, as a cooking agent, to other articles of food or drink.

Such modifications of form, dimensions and materials may be made as fall within the scope of the appended claims.

I claim as my invention:

- 5 1. In a liquid-conductor heater, the combination with a receptacle for a body of liquid, and spaced terminal electrodes of relatively large surface area located therein, of a plate electrode above said terminal electrodes in liquid-conductor relation thereto to cooperate with the body of liquid in conducting a heat-generating electric current between them.
- 10 2. In a liquid-conductor heater, the combination with a receptacle for a body of liquid, and a plurality of spaced terminal electrodes therein having relatively large substantially parallel surfaces, of a plate electrode located adjacent to said terminal-electrode surfaces to cooperate with the body of liquid in said receptacle in conducting a heat-generating electric current between them.
- 15 3. In a liquid-conductor heater, the combination with a receptacle for a body of liquid, and substantially parallel terminal electrodes therein of large surface area, of a perforated plate electrode located adjacent to said terminal electrodes in liquid-conductor relation thereto to cooperate with the body of liquid in conducting heat generating electric current between them.
- 20 4. In a liquid-conductor heater, the combination with a receptacle for liquid, and spaced conducting terminal electrodes adjacent to the bottom thereof, of a plate electrode loosely supported above said terminal electrodes in liquid-conductor relation thereto to cooperate with the body of liquid in which they are submerged to constitute a heat-generating conducting path for electric current.

In testimony whereof, I have hereunto subscribed my name this 12 day of March,
45 1929.

MARSHALL W. HANKS.
